UNITED STATES PATENT OFFICE.

CHARLES STROBL, OF APPLETON, WISCONSIN.

TOOL.

Application filed June 19, 1926. Serial No. 117,146.

This invention relates to tools, and has particular application to a tool for grinding the cylinders of an engine, to render the walls thereof perfectly round and smooth, a necessary condition for efficiency in operation.

In carrying out the invention I contemplate the use of a circumferential series of grinding tools mounted on a frame for rotation therewith, together with a novel construction and arrangement of parts for exerting an outward pressure against said tools to hold them in effective engagement with the wall of the cylinder being dealt with, so that the work can be accomplished in an efficient manner and in comparatively quick order.

Another object of the invention resides in the provision of means for adjusting the grinding tools so as to limit the outward movement thereof under the influence of the yieldable means, thus preventing the cylinder wall from being cut or ground too deeply.

Other objects and advantages will appear when the following detail description is read in connection with the accompanying drawings, and wherein like numerals of reference indicate similar parts in the several views.

Figure 1 is a view in elevation of the tool forming the subject matter of the present invention.

Figure 2 is a sectional view on line 2—2 of Figure 1.

Figure 3 is a sectional view on line 3—3 of Figure 2.

Figure 4 is a plan view on one side of the frame.

Figure 5 is a detail view of one of the rods used with each grinding tool.

Figure 6 is a perspective view of one of the tool holders.

The tool forming the subject matter of the present invention essentially embodies a shaft 10 adapted to be rotated within the cylinder by any suitable means, preferably by a portable electric motor (not shown). Carried by one end of the shaft is a frame-like supporting structure, preferably including spaced plates 11, and while these plates may vary in size and configuration, they are preferably of the shape illustrated in Figure 4. The plates are provided with central openings 12 to receive the shaft 10 and notched as at 13 to accommodate a key 14

by means of which the frame-like structure is held fixed to the shaft. Suitable washers 15 are also mounted on the shaft and arranged to engage the adjacent plates of the frame. The plates 11 are connected together by bolts 16 which connect the corresponding corners of the plates, while also connecting the plates together is a plurality of bolts 17 which are arranged inwardly of the bolts 16 for a purpose to be hereinafter described.

Supported on the frame is a plurality of tools designed to accomplish the above mentioned purpose, and each tool 18 is fixed to a carrier 19 of the construction illustrated in Figure 6. As all of the tools and carriers therefor are identical in construction, a detail description of one will suffice for all.

Each carrier consists of a curved plate 19 provided with suitable openings 20 to accommodate rivets or other suitable fastening elements 21 employed for holding the tool 18 on the carrier. In this connection it might be stated that the openings in the tool are shaped to allow the heads of the rivets or other fastening elements 21 to be counter-sunk, so that they will not come in contact with the wall of the cylinder while the tool is in use. One end of the carrier 19 is rolled inwardly upon itself to provide a tubular portion 22 to receive one of the bolts 16, the latter constituting a pivot upon which the carrier moves toward and away from the wall of the cylinder in the manner to be hereinafter described. The other end of the carrier is offset inwardly as at 23 and then extended outwardly as at 24 to provide an attaching flange for association with a rod 25 which is threaded for a portion of its length as at 26, and formed with an eye 27 at one end thereof. The flange 24 is also provided with a central opening 28 to receive the adjacent rod 25 upon which the carrier slides incident to the pivotal movement of the carrier on its pivot 16. The eye 27 of the rod 25 is received by one of the inner bolts 17, and extends therefrom beyond the edge of the plates 11 of the frame for connection with the adjacent carrier as shown in Figure 2. These rods 25 are arranged centrally of the bolts 17 and maintained in this position by sleeves 29 which surround the bolts 17 at opposite sides of the eye 27 of said rod. Surrounding the rod 25 is a coil spring 30, the ends of which are associated with washers 31 having bend-

able prongs 32 to engage the adjacent convolutions of the spring and thus prevent the spring from twisting upon the rod. The spring 30 has one end bearing against the eye 27 of the rod and its other end bearing against the flange 24 of the carrier, while threaded upon the outer end of the rod is a nut 33 which is utilized to adjust the tension of the spring, and also to limit the outward movement of the carrier and its tool with relation to the wall of the cylinder. This obviously prevents the tool from cutting the wall of the cylinder too deeply as will be readily appreciated. As shown in Figure 2 the tools are arranged circumferentially about the shaft 10, and the number of tools used depends upon the size of the latter, and can be varied without departing from the inventive idea.

In practice it is only necessary to adjust the nuts 33 so as to limit the outward movement of the various tools arranged circumferentially about the shaft 10, and then place the tool in its entirety within the cylinder, wherein the tools are held in effective engagement with the wall of the latter under the action of the springs 30. The shaft 10 is then rotated, and as the wall of the cylinder is ground, the springs gradually move the cutting tools and their carriers outwardly, until the flanges 24 strike the nuts 33, which as above stated prevent further outward movement of said cutting tools. The invention is simple in construction, and highly efficient in operation for the purpose intended.

While it is believed that from the foregoing description, the nature and advantages of the invention will be readily apparent, I desire to have it understood, that I do not limit myself to what is herein shown and described and that such changes may be resorted to when desired as fall within the scope of what is claimed.

What is claimed is:

1. In a tool of the character described, a rotatable shaft, a frame mounted on one end of the shaft for rotation therewith, a circumferential series of tool carriers pivotally mounted on said frame, each carrier terminating to provide an offset apertured

extremity, grinding tools associated with said carriers, rods pivotally supported on said frame and upon which the said apertured extremities of said carriers slide, springs surrounding said rods and arranged to exert an outward pressure on said carriers, and means on the outer ends of said rods for limiting the outward movements of said carriers for the purpose specified. 60

2. In a tool of the character described, a rotatable shaft, a frame comprising spaced plates mounted on the shaft for rotation therewith, inner and outer series of bolts connecting said plates, a circumferential series of tool carriers pivotally mounted on the outer series of said bolts, grinding tools associated with said carriers, rods supported on the inner series of said bolts and projecting beyond the edges of said plates, and slidably supporting the adjacent ends of said carriers, coil springs surrounding said rods and exerting an outward pressure on said carriers, and nuts threadedly adjustable on the projecting ends of said bolts for limiting the movements of said carriers under the influence of said springs. 70

3. In a tool of the character described, a rotatable shaft, a frame comprising spaced plates mounted upon the shaft for rotation therewith, inner and outer series of bolts connecting said plates, a circumferential series of tool carriers arranged about the shaft, each carrier including a curved body portion terminating to provide a loop to receive one of the outer series of bolts, upon which said carriers are pivotally mounted, an offset apertured flange arranged at the other end of each carrier, rods supported upon the inner series of bolts and received by the apertures of said flanges, whereby said carriers are slidable upon said rods, coil springs surrounding said rods and exerting outward pressures upon said carriers, nuts threaded on said rods and adjustable to limit the movements of the carriers under the influence of said springs, and grinding tools mounted on the carriers. 80

In testimony whereof I affix my signature.

CHARLES STROBL.
